UNITED STATES PATENT OFFICE.

JAMES H. WHITE, OF NEW YORK, N. Y., ASSIGNOR TO THE MANHATTAN BRASS COMPANY, OF SAME PLACE.

DESIGN FOR A FENDER.

SPECIFICATION forming part of Design No. 14,676, dated February 12, 1884

Application filed December 29, 1883. Term of patent 3½ years.

To all whom it may concern:

Be it known that I, JAMES H. WHITE, of the city and State of New York, have invented and produced a Design for Fenders, of which

5 the following is a specification.

The design of this fender consists in the molded base *a*, upright *b*, and top rail, *c*, with intermediate sunken panels, *d*, having the stems *e*, leaflets *f*, and flowers *g* in relief, substantially

10 as represented. The ornamental columns *h* support the top rail, the ends of the latter terminating as volutes.

I claim as my design—

The design of the fender, consisting of the base, uprights, rail, intermediate sunken panels, and stems, leaflets, and flowers in relief, substantially as represented.

15 Signed by me this 24th day of December, A. D. 1883.

JAMES H. WHITE.
